(57) **CLAIM**

The ornamental design for a fluid tap, as shown and described.

DESCRIPTION

FIG. 1 is a top front right perspective view of a part of a fluid tap;

FIG. 2 is a front view of the Fluid Tap illustrated in FIG. 1; FIG. 3 is a rear view of the Fluid Tap illustrated in FIG. 1; FIG. 4 is a left side view of the Fluid Tap illustrated in FIG. 1;

FIG. 5 is a right side view of the Fluid Tap illustrated in FIG. 1; FIG. 6 is a top view of the Fluid Tap illustrated in FIG. 1; and,

FIG. 7 is a bottom view of the Fluid Tap illustrated in FIG. 1.

The broken lines shown in the drawings illustrate portions of the fluid tap that form no part of the claimed design.
